(Cl. D52—1)

Fig. 1 is a perspective view of a case for a combined measuring tape and key chain showing our new design;

Fig. 2 is a front view of the case of Fig. 1;

Fig. 3 is an end view of the case of Fig. 1; and

Fig. 4 is a top view of the case of Fig. 1.

The chain and the visible portions of the measuring tape are of a conventional type and are shown in broken lines for the purpose of indicating the relationship of the parts only.

We claim:

The ornamental design for a case for a combined measuring tape and key chain, substantially as shown and described.
